UNITED STATES PATENT OFFICE.

DANIEL BLOMBACH, OF KEENE, NEW HAMPSHIRE.

ATTACHMENT FOR WEAVING MACHINES.

Application filed May 22, 1922. Serial No. 562,710.

To all whom it may concern:

Be it known that I, DANIEL BLOMBACH, a citizen of the United States, residing at Keene, in the county of Cheshire and State 5 of New Hampshire, have invented certain new and useful Improvements in an Attachment for Weaving Machines; and I do declare the following to be a full, clear, and exact description of the invention, such as will 10 enable others skilled in the art to which it appertains to make and use the same.

This invention relates to an improved attachment for weaving machines and one object of the invention is to provide a device 15 which can be connected with the spool-carrying frame and will serve to keep the threads under tension as they are drawn from the spools.

Another object of the invention is to so 20 construct this attachment that a separate tensioning means may be provided for each thread thus permitting the threads to be individually retained under tension, extra strain upon any thread prevented from having 25 any effect upon the remaining threads.

Another object of the invention is to so construct this attachment that the threads while passing through the frame will be prevented from becoming tangled.

Another object of the invention is to so 30 construct this attachment that it can be readily put in place in connection with a conventional construction of spool-carrying board.

Another object of the invention is to provide 35 a device of the character described which will be very efficient in operation and simple in construction.

This invention is illustrated in the accompanying drawings, wherein:

40 Figure 1 is a view showing the device in front elevation and operatively associated with a spool-carrying board.

Figure 2 is a view showing the structure of Fig. 1 in side elevation.

45 Figure 3 is a longitudinal sectional view through the device.

Figure 4 is an enlarged view showing the upper portion of the device in front elevation.

50 Figure 5 is a transverse sectional view taken along the line 5—5 of Fig. 4.

Figure 6 is a transverse sectional view taken along the line 6—6 of Fig. 4.

This device is provided with side bars 1 55 which are preferably formed of solid bars of wood but may be formed of any suitable ma-

terial. These side bars are provided with transversely extending passages 2 forming spring pockets in which are positioned coiled springs 3 which have their outer ends secured to the side bars in any suitable manner, but in the preferred form will have them extended as shown in Fig. 2 and secured by fasteners such as small nails 4 driven into the outer sides of the side bars. These springs 60 have their inner end portions provided with eyes 5 with which the threads will be engaged as will be hereinafter brought out. These side bars are connected by means of cross strips 6 which extend between the side 65 bars as shown in Fig. 6 and have their end portions reduced to provide finger or tongue extensions which are positioned in grooves 7 formed in the outer faces of the side bars and secured by fasteners such as screws 8. 70 Each of these cross strips 6 is provided with thread passages 9 protected by bushings of china or other suitable material to protect the thread, and each of the cross strips carries brackets 10 which extend longitudinally 75 of the strips adjacent the thread passages 9 and carry eyes 11 to be engaged by the threads when the threads are properly threaded through the device. A bridge 12 formed of wire extends longitudinally of 80 each cross strip so that the thread will engage these bridges 12 and thus be protected from wear which might cause breaking of the threads. In addition to the cross strips 85 6, there has been provided a head strip 13 90 which is somewhat similar to the cross strips 6 but is deeper than these cross strips and extends beyond the plane of the outer faces of the side bars so that this head strip can be provided with thread passages 14 which correspond in number to the total number of 95 thread passages in all of the cross strips and will be provided with bushings similar to the bushings placed in the thread passages of the cross strips. A roller 15 is mounted upon 100 an axle bar 16 which has its end portions bent to provide arms 17 which are embedded in the lower ends of the side bars 1. It will, of course, be obvious that if desired, stub pins embedded in the ends of the side bars 105 may be used instead of a single bearing rod.

When this attachment is in use, it is to be connected with the board or creel 18 carrying the spools 19 upon which the thread 20 is wound. In order to do so, the upper 110 ends of the side bars 1 are provided with openings so that fasteners 21 may be passed

through the side bars and firmly hold the device in engagement with the board or creel 18. The threads from the different spools 19 are passed through the thread passages 14 of the head board 13 and are then carried downwardly. The threads engage the bridges 12 so that they are prevented from being worn against the upper edges of the cross strips 6 and pass over the roller 15 to 10 the weaving machine. Each of the threads after being passed through a thread passage of the head board is carried forwardly and upon reaching the bracket of a selected cross strip is passed through the eye 11 carried 15 thereby and is then passed through the eye of a spring carried by one of the side bars and then carried across the space between the side bars and through the eye of a spring directly opposite. After being 20 passed through the eye of the second spring, the thread is passed through a thread passage 9 of the cross strip and is then carried downwardly over the bridges of the cross strips and over the roller. From an inspection 25 of the drawings, it will be readily seen that when passing the threads through the tensioning device, the threads will be preferably carried forwardly in pairs and thus the threads when carried forwardly to the 30 eyes 11 will be positioned between the threads which have been passed through the thread passages of the cross strips. The threads which are passing to the eyes 11 will therefore be confined between threads 35 which have already been engaged with the eyes of the tensioning springs and passed through the thread passages of the cross strips and tangling of the threads will be prevented. As the threads are unwound 40 from the spools 19 during operation of the weaving machine, the springs will be stretched and therefore each thread will be held under tension and kept from running loose. The threads will further be prevented 45 from being easily broken by an extra pull as the springs will permit give and thus prevent breakage.

I claim:

1. A device of the character described 50 comprising a frame for connection with a spool carrying creel, said frame having thread passages at points throughout its

length, bracket elements adjacent the thread passages, thread engaging elements carried by said brackets, and thread tensioning 55 means at opposite sides of the frame for engaging threads after engagement with the bracket carried thread engaging elements and before passage through the thread passages, and a cross head adjacent the upper end of said frame having thread passages corresponding in number to the total number of previously mentioned thread passages.

2. A device of the character described 65 comprising a frame for connection with a spool carrying creel, said frame having side bars and cross strips carried by and extending between said side bars and provided with thread passages, thread guiding means 70 connected with said cross strips, thread tensioning means carried by said side bars for engaging threads after engagement of the threads with said thread guides, and a cross head carried by and extending between the 75 upper end portions of said side bars and having thread passages corresponding in number to the total number of thread passages of the cross strips.

3. The structure of claim 2 and a bridge 80 element extending longitudinally of the edge face of each cross strip.

4. A device of the character described comprising a frame having side bars, cross strips carried by and extending between the 85 side bars and having thread passages, the side bars having transversely extending passages forming spring pockets, springs passing through the pockets and secured at their outer ends and having their inner ends free 90 and provided with thread engaging eyes, brackets carried by said cross strips and extending between said side bars, thread engaging eyes loose upon said brackets, and a bridge element extending longitudinally of 95 the edge face of each cross strip.

5. The structure of claim 4 and an anti-friction roller rotatably mounted beneath the frame and extending transversely of the space between the side bars.

In testimony whereof I have hereunto set my hand.

DANIEL BLOMBACH.
